ATTORNEY

UNITED STATES PATENT OFFICE.

FREDRICK WITTENMEIER, OF COLUMBUS, OHIO.

VEGETABLE-GRATER.

SPECIFICATION forming part of Letters Patent No. 225,313, dated March 9, 1880.

Application filed January 24, 1880.

To all whom it may concern:

Be it known that I, FREDRICK WITTENMEIER, citizen of the United States, residing at Columbus, in the county of Franklin and State of Ohio, have invented certain new and useful Improvements in Vegetable-Graters; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 This invention relates to that class of vegetable-graters in which a vegetable-holding box having a follower, but no bottom, is arranged to be moved backward and forward in ways above a perforated grating-surface.

20 The said invention consists in the improvements hereinafter described, and more particularly pointed out in the appended claims.

In the accompanying drawings, Figure 1 represents a perspective view of my improved 25 vegetable-grater. Fig. 2 represents a top view of the same, with the receiving-box partly withdrawn in a lateral direction and the vegetable-holding box or frame withdrawn longitudinally from the grating-surface, though not wholly 30 withdrawn from its guideways. Fig. 3 represents a vertical longitudinal section through the center of said box when in the position shown in Fig. 1, and Fig. 4 represents a vertical cross-section through the center of the 35 box when in the position shown in Fig. 1.

A designates a receiving-box, into which the gratings fall, and which forms a base for the other devices hereinafter described. The ends of said box A are provided at their top edges 40 with transverse flanges or ledges *a*, extending from side to side of the box and serving as guides for the lateral withdrawal of grating-platform B when the grating is finished. This platform B extends longitudinally beyond said 45 receiving-box A, to give room for the vibration of the vegetable-holding box or frame hereinafter described, and is provided on its side edges with raised side pieces, B', in which are formed longitudinal grooves or guideways 50 *b*. The middle portion of said grating-platform is cut away, and the opening thus made

is covered with a perforated flat grater, C, which extends over the whole interior of receiving-box A. At the ends of this grater transverse strips of rubber or other suitable 55 material are fastened to the top of platform B. These strips (marked *c*) extend far enough at each end to prevent the escape of any particles of the vegetable in either longitudinal direction while the vegetable-holding box or frame 60 is traveling back and forth, as hereinafter described. On the bottom of said platform B are secured transverse guide-pieces B², which are recessed at *b*² to receive the flanges or ledges *a* on box A, above mentioned. 65

D designates a bottomless vegetable-holding box or frame, of rectangular shape, and provided at the bottom edges of its sides with beads or guide-flanges *d*, which set into grooves or guideways *b*. This box is of sufficient size 70 to cover the grater C, and of any convenient depth. It tapers internally from top to bottom, so as to have the shape of a hopper or funnel of slight inclination. This shape facilitates the introduction of the vegetables to be 75 operated on, but causes them to jam tightly together at the bottom of box D, so as to obtain the best possible results from the action of the grater C below.

E designates a follower adapted to pass 80 down into frame or box D, forcing the vegetables through the grater as fast as they are comminuted thereby. Said follower is made smaller than the upper end of the vegetable-holding box or frame D, but fits exactly the 85 lower part thereof, so that no particles of the vegetable will pass up above said follower when the grated, or partly grated, layer of vegetable is reached by said follower. To insure accurate fitting between the latter and box D, 90 the sides or edges of said follower are beveled, having the same inclination as that of the inner faces of said box.

The construction of the follower E and box D, as above described, prevents said follower 95 from passing through said box so as to press against the grater. It is more serviceable for this purpose than stops of any sort, since it does not allow fragments of the grated vegetable to collect where they cannot easily be 100 dislodged. It is also a stronger and more reliable contrivance. The said follower E is pro-

vided on its top with a handle, F, and grasping recesses G. By means of this handle and these grasping-recesses the box D can be moved backward and forward longitudinally to grate the vegetables contained therein. By means of said handle the box D, grater C, and platform B can all be laterally moved off from the receiving-box A, which can then be readily dumped or otherwise emptied. This separation may be total or partial, as seems most convenient.

I do not confine myself to any particular material for the construction of my improved vegetable-grater. Most of its parts can be made cheaply of wood and will answer every ordinary purpose; but any suitable metal may be employed instead. Other changes may obviously be made without departing from the spirit of my invention.

The entire working of the device from the time box D is charged until the time box A is left open for emptying is by means of the handle F with the aid of the recesses G. These recesses afford a firmer hold to the operator's hand; but they are not indispensable. All that is necessary is to set the box A on a table or other support, and steady it there by one hand; then grasp handle F with the other and work it back and forth in a longitudinal direction, giving it full sweep and bearing moderately on the contents of box D till the bottom thereof is reached; then move said handle to the right or left until the receiving-box A is left uncovered for emptying.

The construction of platform B allows a long and effective motion of box D for grating, and

the tight fit of said box and follower, together with the presence of flexible strips *c* and side walls, *b*, prevents the loss of any part of the material operated on. The machine itself will be very little soiled, and the operator's hand is fully protected. There is no need to open or unhinge any part of the device, yet it is readily taken apart for cleaning. I have described it as used for grating vegetables; but it can obviously be applied to other substances also.

Having thus fully described my invention, what I claim as new, and desire to protect by Letters Patent, is—

1. In combination with receiving-box A and platform B, attached thereto by transverse guideways and having grater C, a vegetable-holding box or frame, D, attached to said platform by longitudinal guideways, and a follower, 55 E, having handle F, whereby box D is moved longitudinally, and box D and platform B laterally, at will, substantially as set forth.

2. In combination with receiving-box A, platform B, and grater C, the internally-tapering or hopper-shaped vegetable-holding box or frame D, and the follower E, having its edges correspondingly inclined, and adapted to fit tightly the interior of said box D at the bottom thereof.

In testimony whereof I affix my signature in presence of two witnesses.

FREDRICK WITTENMEIER.
